UNITED STATES PATENT OFFICE.

RALPH P. STEVENS, OF STANFORD UNIVERSITY, CALIFORNIA.

TICKET-PUNCH.

1,112,573.

Specification of Letters Patent.

Patented Oct. 6, 1914.

Application filed June 11, 1913. Serial No. 773,043.

To all whom it may concern:

Be it known that I, RALPH P. STEVENS, a citizen of the United States, residing at Stanford University, in the county of Santa Clara and State of California, have invented 5 a new and useful Ticket-Punch, of which the following is a specification in such full and clear terms as will enable those skilled in the art to construct and use the same.

10 This invention relates to a ticket or check punch, and its object is to produce a small but compact punch capable of being made very cheaply and so constructed as to be capable of producing several different characters, and which is provided with a receptacle for the punchings to prevent them from being scattered upon the floor or carpet.

An embodiment of the invention is shown 20 in the drawings which are upon a larger scale than is contemplated for the actual machine and in which the same reference numeral is applied to the same portion throughout, but I am aware that there are 25 many modifications thereof.

Figure 1 is a side elevation partly in section of the complete punch, Fig. 2 is a plan view thereof, Fig. 3 is an end elevation of the punch looking in the direction indicated by the arrow, Fig. 1, Fig. 4 is a side elevation of the receptacle for the punchings, and Fig. 5 is a view showing one of the characters and the die used in conjunction therewith.

35 The numeral 1 represents a spring steel strip bent into a U shape and having the ends thereof bent out to form two substantially cylindrical boxes 2 and 3. The upper box 2 is inclosed on one side as indicated at 40 4 and has the die cylinder fitting snugly therein. This die cylinder comprises a steel die strip 5 secured to two disks 6 and 7, the latter having holes therein to permit the clippings to be dropped out of the box 45 while the former has lugs 8 pressed therein adjacent each die opening to enable the dies to be accurately set, the lugs taking in turn in a notch in the edge of the box 2 in the proper position to hold the dies opposite the 50 punch. A screw 9 extends through the side of the box 2 and is connected with the die box to hold the latter in place, said box being removable at the side of the box 2. Secured to one of the arms of the strip 1 is a 55 stripper plate 11, said stripper plate having

its outer end bent downwardly as indicated at 12 to prevent the paper from being inadvertently placed in the wrong position.

The box 3 has the die block 13 therein, said die block carrying a plurality of male 60 dies 14 extending radially therefrom. This die block is so placed with respect to the box 3 that its dies extend out of the box on one side thereof, a screw 15 holding it in the given position. This screw is secured to the 65 die block and carries a plate 16 on the outside thereof which bears upon a plate 17 forming one end of the box 3. The latter plate has openings therein in which lugs 18 on the plate 16 take in thereby enabling the 70 user to set the male dies in the precise position desired to punch any given letter or character. It will be understood that the plate 17 and the plate forming the exposed 75 side of the female die box are each lettered to enable the user to know what two dies to bring together to produce the desired character.

It will be understood that while the two cylindrical boxes supporting the male and 80 female dies respectively are shown secured to a single strip of metal, that any suitable means may be used for their support.

Having thus described my invention what I claim as new and desire to secure by Letters Patent of the United States, is as follows, modifications within the scope of the 85 claims being expressly reserved:

1. A punch comprising a pair of cylinder-like receptacles, a spring securing said receptacles together, a revoluble male die block carried within one of said receptacles, a revoluble female die box within and having substantially its entire periphery in contact with the interior of the other receptacle, the 90 outer surface of said female die box lying in substantially the same plane as the inner face of the spring to which said receptacle is secured, and a circular cover secured to the female die having lugs on the side thereof to engage notches in the box to hold the die in a given position.

2. A punch comprising a pair of cylinder-like receptacles, a spring securing said receptacles together, a revoluble male die 105 block carried within one of said receptacles, a revoluble female die box within and having substantially its entire periphery in contact with the interior of the other receptacle, the outer surface of said female 110

die box lying in substantially the same plane as the inner face of the spring to which said receptacle is secured, a stripper plate secured to the spring and extending between the two receptacles, a circular cover secured to the female die having lugs on the sides thereof to engage notches in the side of the die box to hold the die in a given position and a plate connected to the male die and having lugs on the side thereof to engage the die

box and hold the male die in a given position.

In testimony whereof I have hereunto set my hand this 6th day of June A. D. 1913, in the presence of the two subscribed witnesses.

RALPH P. STEVENS.
